UNITED STATES PATENT OFFICE

138,799

DESIGN FOR A DOLL

Frank Alma Cartee, Coral Gables, Fla.

Application May 26, 1944, Serial No. 113,758

Term of patent 7 years

(Cl. D34—4)

To all whom it may concern:

Be it known that I, Frank Alma Cartee, a citizen of the United States, residing in Coral Gables, Dade County, State of Florida, have invented a new, original, and ornamental Design for a Doll, of which the following is a specification, reference being had to the accompanying drawing, forming a part hereof, in which:

Fig. 1 is a front elevation of a doll embodying my new design; and

Fig. 2 is a rear elevation thereof.

I claim:

The ornamental design for a doll, as shown.

FRANK ALMA CARTEE.
